CLOTHES WASHING MACHINE

Robert Bruce Morrison, Detroit, Mich.

Application March 13, 1931, Serial No. 522,471

4 Claims. (Cl. 68—15)

My invention relates to improvements in clothes washing machines of the type having a stationary upright tub and the objects of my improvements are, first, to provide means of raising the clothes in a washing machine tub after they have been washed and so eliminate the necessity of probing underneath the water in reclaiming the clothes preparatory to putting them through a wringer or dryer, that is, the clothes nearer the tub bottom are raised into view as fast as the upper clothes are removed from the tub and the pieces are more easily extricated from the tangled clothing also lightening the work of getting the pieces to the wringer or dryer; second, to eliminate the usual procedure of putting the hands deep into hot water thus allowing also for the use of hotter water in the tub.

One form of the invention is illustrated in the accompanying drawing in which Figure 1 is an elevation of the main body of a clothes washing machine with a section cut away to show the parts. Figure 2 shows an arrangement of the parts about the drive shaft which will permit use of the invention. Figure 3 shows the end fork of lever 2. Figure 4 is a plan section through the vertical drive shaft and sleeves. Figure 5 is a perspective view for special washers to be used in connection with the stuffing box for sealing the tub about shaft 1 of top part of Figure 2. Figure 6 is a plan section partly broken away taken just below the washer tub of Figure 1. Figure 7 is a fragmental section taken at the outer circumference of the agitator disc 7 showing a relation that it could have with pan 8 of Figures 1 and 9. Figure 8 is also a fragmental section taken at the outer circumference of the agitator disc but illustrating a depression in pan 8 to receive a turnable button which could be used at necessary intervals for the purpose of introducing or withdrawing a projection or lap under the bottom of the agitator disc. Figure 9 is a sectional view showing an arrangement for the supplementary bottom pan 8 in relation to an agitator disc 7, and washer tub bottom 11. Figure 10 is a detail of the hinged connection of lever 2 on bracket 32, on leg 12. Figure 11 shows the connection between parts 3 and 4 of Figures 1 and 6.

As this invention is intended only as an improvement adaptable to standard makes of clothes washing machines having the stationary tub and having some power driven means for drying the clothes somewhat, I am aware that many different arrangements may be used within the scope of this invention. The illustrations therefore

represent only a random possibility of no particular make of washer.

In Figure 1, part 1 is a shaft the upper end of which is inside the washer tub. The parts surrounding shaft 1 are designed to allow the shaft to be raised. At the lower end of shaft 1 is thrust bearing 18, having opposite projecting pins 17 which engage the slots 19 in the prongs of the fork of lever 2 which is hinged as at 32, Figure 10 to the washer frame. For this arrangement the lever is connected at an intermediate point by a spring 3 to the end of a crank 4 which is a rigid part of and is hand operated by lever 5 which ratchets about the notched arc 6 through the medium of catch 30, for securing lever 5 against retrograde movement from any desired setting. When shaft 1 is raised by the above mechanism it necessarily forces the secondary bottom, which may be a combination of the agitator disc 7 and the pan 8, up from the bottom 11 and to a position well up in the washer tub as illustrated.

It is important that the spring 3, shall when stressed, be enough to raise readily, only the maximum capacity of wet clothes; that is it is intended that the water, which is not held in suspension within the clothes proper, must seep through to the bottom of the tub during the steady upward pressure as applied by this spring or by a similar medium, rather than to attempt to raise all the water. Therefore the real function of the spring in stress, is to allow a time interval in which the water can recede, consequently saving time and effort for the operator.

Parts 9 are tie members across the lower legs 12 and if used may serve to support thrust bearing 17, laterally and perhaps vertically.

Figure 2 is made up of part 1 which is a shaft structurally free to raise vertically the desired distance through the hollow shaft 13 and the stuffing box 21 with its special shaped washers 22, the keyway 24 meshing with the lug on the inside circumference of the packing retaining washers 28 for sealing the tub about the shaft. Keyway 24 meshes with the key 23 which is rigid to the hollow shaft which in turn is rigid, through key 34, to the power driven gear 26 which is of the conventional pattern. Part 33 is of the conventional gear enclosure. Other parts also of this Figure 2 are dependent upon standardized practice of the various manufacturers and are not within the scope of this invention.

Figure 3 gives an isometric view of the end of lever 2 showing the prongs with slots 19 for engaging pins 17 projecting from the outer circumference of the end bearing 18 of shaft 1. The

purpose of the slots 19 being to compensate for the variable effective length of lever 2 as measured from the hinged point on the frame to the centerline of the pins 17 when engaged in the slots and 5 while the lever and shaft are raised and lowered within their limits.

Figure 4 is a section taken just below part 15 of Figure 2 showing shaft 1 with its keyway 24, and the key 23 which is rigid to hollow shaft 13 but 10 which has sufficient freedom in keyway of shaft 1 to allow said shaft to slide freely vertically. Part 14 is the outside sleeve which is rigid to the bottom of the washer tub.

Figure 5 is an isometric view of a shape for the 15 washers for retaining the packing used in the stuffing box 21 and showing a lug on the inside circumference, a necessary feature for holding the packing which seals the keyway 24 in shaft 1. The packing ring itself will have the same general 20 shape.

Figure 6 is a plan section of Figure 1 taken just 15 below the tub bottom 11 and showing a possible relation between parts 1 to 6 inclusive, also part 30, which is a conventional spring held pin-detent 25 or pawl.

Figure 7 shows an arrangement which may be 30 used between the agitator disc 7 and a supplementary bottom ring 8, for those types of washing machines which have the agitator disc near the bottom of the washer tub. The outer circumference of the agitator disc has an angular shape 35 adjoining the inner circumference of the pan ring 8. Because the agitator rocks or oscillates horizontally, parts 7 and 8 must not be in contact except when these parts are to be raised in the tub by the mechanism described and therefore the pan 8 must rest on the tub bottom when the pan is not raised.

Figure 8 is a detail section showing a fragmental part of the outer circumference of the agitator disc 7 and of the inner circumference of the pan 8, the latter to rest upon the tub bottom or side. When lowering the agitator disc to its bottom position in the washer tub the pan 8 may 45 lag behind unless held in the same plane with said disc. I overcome this by using a button 25 turned by the fingers within a depression formed in the bottom of part 8 so that a part 26, which is connected to button 25 and to pan 8, turns a like 50 angle to introduce a projection under the part 7 or to withdraw such projection as may be required. The section through part 8 as shown in Fig. 8, applies only where the fasteners 25 and 26 occur, possibly four fasteners in all.

Figure 9 shows the combined bottom which in 55 the low agitator type of machine may be made up of parts 7 and 8. Parts 31 in Figure 9 are well rounded hand holds for lifting pan 8, possibly with the aid of a hinge or joint at 27 for collapsing 60 the pan if built in parts. Parts 7 and 8 are apertured as at 28, to provide ready passage of the water in either direction.

In Figures 1, 2, and 9 it is optional whether 65 stuffing box 21 is placed at the lower end of the hollow shaft 13, that is, outside the tub and inverted from the way I have shown, or at the upper end as shown. If placed within the tub there is the advantage that dirt and grit will not enter the keyway 24 to hamper sliding movement.

70 Operation of the machine illustrated is as follows:

After the tubful of clothes has been washed and the agitation as conventionally affected through the power-driven movements of the 75 vertical shaft 1 has been stopped, the lever 5 is

swung to the desired setting thus raising crank 4 and stressing spring 3 which is attached to lever 2. But lever 2 will lag behind, rising only as the bulk of the water in the tub seeps through to the space below the elevating pan 8. When the spring is 5 released the pan will quickly drop back into place in the bottom of the tub since there will be no clothes to impede the flow of water in this direction.

I claim:

1. A clothes washing machine comprising an upright stationary tub, a slidable shaft projecting into said tub through the bottom, an agitator having a sleeve mounted on said shaft, a perforated disc plate extending from and connected to the bottom of said sleeve, a pan in the form of a ring having a flange portion surrounding the peripheral edge of the said plate in overlapping relation and spaced therefrom, and having an apertured upwardly flaring portion merging in 20 said flange, a lever slidably connected to the shaft, and means for moving the lever to raise said shaft, said agitator and said ring.

2. A clothes washing machine comprising an upright stationary tub, a slidable shaft projecting 25 into said tub through the bottom, an agitator having a sleeve mounted on said shaft, a perforated disc plate extending from and connected to the bottom of said sleeve, a pan in the form of a ring having a flange portion surrounding the 30 peripheral edge of the said plate in overlapping relation and spaced therefrom, and having an apertured upwardly flaring portion merging in said flange, turnable buttons in recesses in the inner rim of said ring, latches normally overlapping the lower side of the peripheral edge of said plate, said latches actuated by said turnable buttons for the reception of said overlapping of the lower side of said peripheral edge of said plate, 35 breaking joints for collapsing said flanged ring 40 parts.

3. A clothes washing machine comprising an upright stationary tub, a slidable shaft projecting into said tub through the bottom, an agitator having a sleeve mounted on said shaft, a perforated disc plate extending from and connected to the bottom of said sleeve, a pan in the form of a ring having a flange portion surrounding the 45 peripheral edge of the said plate in overlapping relation and spaced therefrom, and having an apertured upwardly flaring portion merging in 50 said flange, a lever slidably connected to the shaft at one end and pivotally connected at its other end to an immovable part of the tub, a crank on the tub and a contractile spring between the 55 crank and an intermediate part of the lever.

4. A clothes washing machine comprising an upright stationary tub, a slidable shaft projecting into said tub through the bottom, an agitator having a sleeve mounted on said shaft, a perforated disc plate extending from and connected to the bottom of said sleeve, a pan in the form of a ring having a flange portion surrounding the 65 peripheral edge of said plate in overlapping relation and spaced therefrom, and having an apertured upwardly flaring portion merging in 70 said flange, a sleeve surrounding the slidable shaft, a slidable keyway engaging shaft and keyway against relative oscillation, a mechanical connection for power drive to the agitator on said sleeve, a ring and keyway packing ring on said shaft, ring and keyway washers adjoining said packing ring, a compression cap encircling said shaft on said sleeve.

ROBERT BRUCE MORRISON.
